UNITED STATES PATENT OFFICE.

EDWARD THOMAS LEWIS, OF OCEANPARK, CALIFORNIA.

STOPPING ATTACHMENT FOR WATCHES.

1,230,733.

Specification of Letters Patent. Patented June 19, 1917.

Application filed November 12, 1915. Serial No. 61,067.

To all whom it may concern:

Be it known that I, EDWARD T. LEWIS, a citizen of the United States, and a resident of Oceanpark, in the county of Los Angeles and State of California, have invented a new and Improved Stopping Attachment for Watches, of which the following is a full, clear, and exact description.

The invention relates to stopping attachments for watches such as shown and described in the application for Letters Patent of the United States, No. 41088, filed by me on July 21, 1915.

An object of the invention is to provide a new and improved stopping attachment for watches such as are loaned by watch repairers to customers, the arrangement being such that the loaned watch, even if wound up regularly by the customer, automatically stops after, say, a week, two weeks or other length of time predetermined by the watch repairer, to induce the customer to return the loaned watch within a reasonable time or to pay for the repairs on his own watch. Another object is to permit of applying the stopping attachment to any make of watch without disorganizing the parts of the watch movement.

In order to accomplish the desired result, use is made of means for automatically engaging one of the train of wheels of the watch movement after the lapse of a predetermined time.

A practical embodiment of the invention is represented in the accompanying drawings forming a part of this specification, in which similar characters of reference indicate corresponding parts in all the views.

Figure 1 is a face view of a watch provided with the stopping attachment, portions of the bezel and the dial being shown broken out;

Fig. 2 is a similar view of the same with the bezel and dial removed;

Fig. 3 is a similar view of the same with the parts in a different position;

Fig. 4 is an edge view of the attachment as applied to the watch movement; and

Fig. 5 is a perspective view of a portion of the dial showing the indicating recess.

As illustrated in Figs. 1 and 2, the hour

wheel 10 of a watch movement of the usual construction is provided with a pin 11 adapted to mesh with the teeth of a mutilated index wheel 12 mounted to turn on a pivot 55 13 attached to the front plate 14 of the watch frame. The under side of the index wheel 12 is provided with a pin 15 adapted to engage the beveled end 16 of a lever 17 fulcrumed at 18 on the front plate 14, and 60 the said lever 17 is provided at its other end with a pin 19 adapted to engage the teeth of the fourth wheel 20 of the train of wheels of the watch movement to stop the latter, as hereinafter more fully explained. The 65 lever 17 is pressed by a spring 21 held on the plate 14 to normally hold the pin 19 out of engagement with the fourth wheel 20. The free end 16 of the lever 17 normally rests against the peripheral face of the hub 70 22 of the index wheel to limit the swinging movement of the lever and to aid a friction washer under the index wheel 12 to prevent accidental turning of the latter. The mutilated index wheel 12 is provided with 75 twenty-two teeth and two teeth are cut out to provide a space 32, and alternate teeth are provided at their faces with numerals arranged in consecutive order from 1 to 10. The alternate tooth next to the tooth marked 80 "10" is provided with an "X" mark, and the two teeth next following the one marked "1" bear zero marks, as plainly indicated in Figs. 2 and 3. The peripheral edge of the index wheel 12 projects into a cut-out portion 23 in the watch case 24, and over this cut-out portion lies a correspondingly shaped plate 25 projecting from the edge of the dial 26. The plate 25 is provided with a cut-out 85 portion 27 to display one of the index numerals, the "X" mark or the zero marks whenever the index wheel 12 is turned correspondingly. The plate 25, its cut-out portion 27 and the tooth of the index wheel 12 appearing in the cut-out portion 27 at the 90 time are hidden by the bezel 28 so that the customer can not see any part of the stopping attachment. When the watch is running, the pin 11 engages one of the teeth of the index wheel 12 every twelve hours and consequently the index wheel 12 is intermittently turned twice each day, and during 95 100

the time the pin 11 engages the tooth marked "6" and the next following tooth the pin 15 engages the beveled end of the lever 16 to impart a swinging movement thereto, and when the mutilated portion 32 is in register with the pin 11 the latter can travel uninterruptedly without affecting the attachment.

The index mark "X" on the index wheel 12 is so arranged relatively to the cut-out portion 32 that when the said mark "X" appears in the recess 27 then the cut-out portion 32 is in the path of the pin 11 and consequently the watch can run indefinitely when properly wound up. When either of the index marks "O" appears in the recess 27 then the watch is prevented from running as the pin 19 now engages the fourth wheel 20 with the tooth marked "6" now standing in the path of the pin 11. When the watch is to be loaned to a customer the repairer temporarily removes the bezel 28 unbeknown to the customer, sets the index wheel 12 so that one of the index numerals from 1 to 10 appears in the recess 27, and then the repairer replaces the bezel. When the watch is now wound up regularly and is running then the pin 11 turns the index wheel 12 a corresponding number of days, that is, at the last day the pin 11 moves into engagement with the tooth of the index wheel 12 marked "6" and turns the index wheel so that the pin 15 now imparts a swinging movement to the lever 17 to engage the pin 19 with the fourth wheel 20, thus stopping the movement. Thus if the repairer desired the return of the watch say in seven days he turns the index wheel 12 until the numeral "7" of this index wheel 12 appears in the recess 27. It will be noticed that the watch when properly wound up by the customer will run seven days and on the seventh day the pin 11 engages the tooth marked "6" and turns the index wheel 12 so that the lever 17 is actuated as previously explained to stop the watch movement by the pin 19 engaging the fourth wheel 20.

In practice, the hour hand 29 of the watch 50 extends over the pin 11 so that the watch repairer when setting the watch for any given length of time can readily turn the hour wheel 10 in such position that its pin 11 is out of mesh with the index wheel 12 to allow 55 convenient turning of the same until the desired position is reached.

In order to accommodate the numeral "5" on the index wheel 12 at the cut-out portion 32 use is made of a half tooth for the 60 numeral 5, but this half tooth is not in the path of the pin 11.

It is understood that when it is desired to have the watch run for an indefinite time or to be sold as a regular timepiece, the watchmaker simply turns the index wheel 12 until

the tooth marked "X" registers with the recess 27. It is further understood that an index wheel with a more or less number of teeth may be used for different periods of time at which the watch is to stop automatically even if wound up to its fullest extent. 70

In order to set the index wheel the watch repairer need only remove the bezel holding the crystal to obtain access to the index wheel at the cut-out portion 32 for turning 75 the index wheel to the desired position. After the index wheel is set the hands may be set either way without disarranging the automatic stop. In my previous application above referred to it is necessary that 80 wheels with a more or less number of teeth are used for different periods of time at which the watch is to stop automatically while in my present invention use is made of a single index wheel which can be set for a 85 given period of time.

Having thus described my invention, I claim as new and desire to secure by Letters Patent:

1. A watch provided with a stopping attachment, comprising a mutilated toothed index wheel having a pin, a stopping lever controlled by the said pin and adapted to engage a movable part of the watch movement, and a pin on one of the wheels of the 95 watch movement and adapted to impart an intermittent motion to the said index wheel until it reaches the mutilated portion of the index wheel.

2. A watch provided with a stopping attachment, comprising a mutilated toothed index wheel provided with consecutive numerals, a pin on the said toothed wheel, a spring-pressed lever adapted to be engaged at one 100 end by the said pin, the said lever having at 105 its other end an arm adapted to engage one of the wheels of the train of wheels of the watch movement, and a pin on one of the driven wheels of the watch movement and adapted to impart an intermittent movement 110 to the said index wheel.

3. A watch provided with a stopping attachment, comprising a mutilated index wheel having a pin, a spring-pressed lever adapted to be engaged by the said pin, the 115 lever having an arm adapted to engage the fourth wheel of the train of wheels of the watch movement, and a pin on the hour wheel of the watch movement and adapted to engage the said index wheel to impart an intermediate movement to the same until the pin reaches the mutilated portion. 120

4. A watch provided with a stopping attachment, comprising a mutilated index wheel having a pin and consecutive numerals 125 adapted to appear in a cut-out portion of the dial, the said cut-out portion being hidden by the bezel, a spring-pressed lever adapted to be engaged by the said pin, the lever having an arm adapted to engage the 130

fourth wheel of the train of wheels of the watch movement, and a pin on the hour wheel of the watch movement and adapted to engage the said index wheel to impart an intermittent movement to the same until the pin reaches the mutilated portion.

In testimony whereof I have signed my

name to this specification in the presence of two subscribing witnesses.

EDWARD THOMAS LEWIS.
